UNITED STATES PATENT OFFICE

2,610,530

PIPE REAMING AND BURRING ATTACHMENT
FOR PIPESThomas A. Caliendo, South Ozone Park, N.Y.
Application May 4, 1950, Serial No. 159,983

2 Claims. (Cl. 77—73)

1

This invention relates to a reaming and burring implement and in particular to one used in the ends of pipes.

A particular object of the invention is to provide a tool, complete in itself which can be detachably mounted on the end of a pipe, held in a vise, and operated to remove the burr from the open cut end of the pipe either before or after the latter has been threaded.

Tools of this character have, to a large extent been contemplated in connection with a thread cutting stock and die implement and the use thereof has been curtailed in the absence of such implement upon which the attachment can be mounted. This type is shown in prior patents such as my Patent 2,458,681 and in my application for patent Serial No. 65,656, filed December 16, 1948, now Patent No. 2,547,195, issued April 3, 1951. However, there are a great many instances where pipe delivered to a job for use needs burring and with this in mind my invention contemplates a tool which can be fitted to the end of a pipe and be ready for the burring operation immediately; one which is single in structure and has the parts so arranged that the tension of the burring cutter can be closely and continuously controlled; one in which adjustment of the cutter is a simple manual operation and one to which rotary manual power may be applied to complete the reaming operation rapidly and accurately.

A still further object is to provide a reamer which can accommodate pipes of different diameters; which can be adjusted to the end of the pipe without any special tools or knowledge and one which has a minimum number of parts which are readily dismantled for replacement, sharpening or repair.

With these and other objects in view, the invention comprises certain construction hereinafter described and then particularly pointed out in the claims and a preferred embodiment of my invention is illustrated in the accompanying drawings in which:

Figure 1 is a side view of a tool constructed in accordance with my invention and showing the manner of mounting the same over the end of a pipe to be reamed.

Figure 2 is an enlarged section taken through the cutter mounting means and the bridge portion of the tool to show how the tension on the cutter is controlled.

Figure 3 is a fragmentary portion of the lower end of the implement shown partly in section to illustrate the means of accommodating pipes of various sizes.

Figure 4 is a section taken on the line 4—4 of Figure 3 further showing the pipe supporting ring structure.

Figure 5 is a side view of a tool showing a modified structure including a ratchet operation which can be used to regulate the tension of the cutter spring and the cutting operation.

Figure 6 is a section taken on the line 6—6 of Figure 5 showing the relative adjusted positions of the ratchet arm and associated parts.

Figure 7 is an enlarged vertical section taken through the adjustable parts of the holder showing the relative positions thereof, and

Figure 8 is a fragmentary view similar to Figure 5 showing an adjusted position of the cutter tensioning means.

Referring to the drawings in detail, 10 indicates a piece of threaded or unthreaded pipe, the open end of which is to be reamed to remove the burr left by the threading dies or the cutting tool, and to which end is to be fixed my novel reaming tool. The latter consists of a yoke 11 including integral leg portions 12 terminating at the inner end of the tool in a pipe encircling collar 13 and at the outer end in a bridge 14 extending diametrically across the end of the pipe but spaced therefrom sufficiently to permit a reaming cutter 15 to be seated in the open end of the pipe 10.

The bridge 14 is drilled to provide a bore 16 and a shouldered recess 17 arranged concentrically with respect to the cutter so that a spindle 18 threaded at its upper and lower ends as at 19 and 20 respectively can pass freely through the unthreaded bore 16. The lower end 20 is tightly threaded into a tapped hole 21 in the upper end of the cutter 15 so that the spindle and cutter for the purpose of the invention may be considered a unitary structure. The upper threaded end 19 of the spindle extends beyond the bridge 14, is adapted to receive the nut 22 and seats in a threaded socket 23 formed at the center of a turning arm 24 used in revolving the cutter to carry out the reaming operation.

In these tools, a factor in their operation has been the constant adjustment necessary to maintain adequate tension on the spring so that the cutter is urged into the end of the pipe with sufficient pressure to obtain an even reaming cutting action and in order to simplify the adjustment as much as possible so that the latter can be accomplished with a minimum of time and effort I have positioned spring 25 about the spindle 18 so that one end seats in the recess 17 and the opposite end bears against the upper surface of the cutter. By turning the nut 22 down on the

can be held in a vise or has been partly assembled in a pipe line.

My invention is not to be restricted to the precise details of construction shown since various changes and modifications may be made therein without departing from the scope of the invention or sacrificing the advantages to be derived from its use.

What I claim is:

1. A pipe reaming tool comprising a yoke including legs, a bridge and a threaded collar at opposite terminal ends of said legs, sleeve means for fixing the tool to a pipe and into which said collar is adjustably threaded to move the bridge with respect to the end of a pipe held in said sleeve means, said bridge being drilled centrally to provide a smooth bore substantially concentric with said pipe, a spindle having a threaded end freely passing through said bore, a reamer mounted on the lower end of said spindle a spring between the reamer and said bridge, a nut on the threaded end of the spindle beyond the bridge for moving the reamer toward the bridge to place the spring under tension when the nut is adjusted against the bridge, manual turning means on said spindle for operating said reamer to ream the pipe and said turning means being movable to thread the collar into said sleeve to place the spring under tension independently of said nut.

2. A pipe reaming tool comprising a yoke including legs, a bridge and a collar portion, means for adjustably securing the collar to a pipe near the end thereof to be reamed, including a sleeve threaded to said collar and a screw for securing the sleeve to the pipe, a reamer seating in the end of the pipe, a threaded spindle secured in the reamer and extending through and beyond a smooth bore in said bridge, a spring on said spindle between said bridge and reamer for applying pressure to the latter, a nut on the spindle beyond said bridge and engageable therewith for compressing the spring when the nut is threaded on the spindle and a handle engaging one of said legs for revolving the spindle, the reamer, and the yoke until the depth of cut by the reamer positions the nut away from the bridge for subsequent adjustment on the spindle.
